UNITED STATES PATENT OFFICE.

CHARLES L. GOODRUM, OF URBANA, OHIO, ASSIGNOR, BY MESNE ASSIGNMENTS, TO
WESTERN ELECTRIC COMPANY, INCORPORATED, A CORPORATION OF NEW YORK.

TELEPHONE SYSTEM AND APPARATUS.

1,226,966.

Specification of Letters Patent.

Patented May 22, 1917.

Original application filed April 1, 1905, Serial No. 253,227. Divided and this application filed February 3, 1910. Serial No. 541,811.

To all whom it may concern:

Be it known that I, CHARLES LANE GOODRUM, citizen of the United States, residing at Urbana, in the county of Champaign and State of Ohio, have invented certain new and useful Improvements in Telephone Systems and Apparatus, of which the following is a specification.

My present invention relates to and has 10 for its object to provide improved electromagnetically operated switches adapted particularly for use in connection with automatic telephone systems, such as the one illustrated in my prior application, Serial 15 No. 253,227, filed April 1, 1905, entitled Telephone systems and apparatus of which this application is a division.

While switches embodying my invention 20 may be used for purposes other than the one mentioned, they relate more particularly to the art of telephony and are adapted to be employed in making connection between two 25 or more telephone lines or the trunk circuits of an automatic telephone exchange arranged between and interconnecting a plurality of such switches. The automatic switch of this invention comprises a movable contact member and groups of contact terminals arranged in a row with which said 30 contact member coöperates, electromagnetic means being provided for moving said contact member past said terminals to select a group thereof, and for controlling the return of said contact member to effect the 35 selection of a contact terminal in the selected group.

In the drawings:

Figure 1 is a plan view of a switch constructed in accordance with my invention.

40 Fig. 2 is a longitudinal view thereof taken on the line 2^x—2^x of Fig. 1.

Fig. 3 is a detail sectional view taken on the line 3^x—3^x of Fig. 2.

Fig. 4 is a detail of some of the contacts 45 and the manner of supporting the same.

Similar reference characters in the several figures indicate similar parts.

In the present case, instead of employing the double motion switches commonly 50 known as the Strowger switches the same having been improved by Messrs. Lundquist, Ericson and others, I have adopted a very different design. In the first place,

my switches are all mounted upon flat bases, so they can be mounted like drawers in a 55 cabinet; and in the second place I make them separable, one part carrying the contact banks and multiple wiring connections, and the other part carrying the relays and the working magnets together with the 60 switch arms or wipers. These second parts are provided with contact terminals which when the parts are in position register with corresponding terminals on the first parts, completing the connections of the relays, 65 etc. These second parts are removable and all of the same kind are interchangeable, and as it is with these parts that a very large percentage of the troubles occur, it is obvious that I have achieved an important 70 end by this arrangement; for in case of any trouble with the working parts of a switch, it is only necessary to slide out the defective switch body and slide in another in its place. 75

I have chosen to depart from the decimal system of trunking because thereby I can simplify the switches and get better results. In the ordinary Strowger switch it is customary to step up the switch arm to the row 80 of contacts desired, and then operate a so-called rotary magnet which would carry the wiper around continuously until it rests upon an idle contact. In the present case I provide fifty contacts in the switch divided 85 into groups of five. The groups of five small contacts are equal in angular dimension and each is overlaid by a single broad contact. Each switch has a double ratchet motion; a pawl working into a coarse 90 ratchet first steps the wipers around to the group contact desired, clearing five of the small contacts at a jump; then an escape- 95 ment pawl working into a finer ratchet (five to one of the other) steps back the wipers one step at a time in the group thus selected. Thus in these switches I only give five trunks to a switch, and I can multiply the number of switches if desired. 100

In illustrating my invention I have shown the switch mechanism mounted upon a base comprising the parts E and e, divided on the line e¹, the former comprising a base upon which operating mechanism is mount- 105 ed, which is removable from the part e, the

latter being provided with the bank of contacts F and being adapted to be rigidly attached or supported on a circuit frame or within a cabinet so that the removable part 5 of the base E may be applied thereto.

Upon the base e is a row of socket contacts H mounted in insulation, with which coöperate the contact terminals h mounted in a strip on the base E. These terminals h 10 are used to complete the circuit to the magnets shown on the base E hereinafter referred to.

The contact banks F are formed as an arc 15 of a circle somewhat less than 180° and concentric with the center or axis b of the switch spindle. In the banks are the broad contacts 48 and individual trunk contacts m⁶.

The switch mechanism comprises a progressively movable element b⁴ which is 20 adapted to be advanced step by step and to this end is made circular in form and is mounted on the revoluble shaft b, the lower end of the shaft being journaled in the base plate E, the other end being journaled in a 25 bracket e², the ends of which are extended downwardly and are detachably secured to the base plate by fastening devices, such as screws. Carried on the movable element and 30 insulated therefrom and from each other are contact springs or wipers indicated by b¹, b² b²⁰⁰, b³, b³⁰⁰. Any desired number of these wipers may be employed and they are arranged as shown one below the other and have 35 at their rear ends segments, as indicated by b¹⁹, with which coöperate spring brushes b²⁰ supported in an insulated holder 4 secured to one of the legs of the bridge. Each brush has a tail b¹¹ for the attachment of 40 its circuit wire and an extension b¹² which receives the wiper when turned all the way around to clear it from the bank contacts and hold it in proper position for reengagement therewith; this clearing being necessary 45 when the plate E and its attached parts are removed from the bank. To facilitate the removal and replacing of the plate in proper alinement with the plate e of the banks, I provide a pair of guide tongues e² attached 50 to the plate e and overlying the plate E when in position. The bank as a whole is carried on four posts p, best shown in Figs. 3 and 4, and each bank of contacts is built up of insulating segments with the contacts 55 radially interposed between them, the whole being held together by upper and lower segmental plates f secured by through-bolts or screws f¹. Connected to the lower end of the shaft b is a coil-spring b⁶ arranged in 60 a casing to which its outer end is attached, the tension applied to the spring being sufficient to return the shaft and the parts supported thereon to their normal position, shown in Fig. 1, when they are released.

65 Coöoperating with the ratchet teeth b⁶ on

the wheel b⁴ is a pawl b¹⁶ on a dog b¹⁴, pivoted in a yoke attached to the base plate E, as shown in Figs. 1, 2 and 3. The dog has a joint in the middle and a spring normally tending to throw it up with the pawl 70 engaging teeth b⁶. Coöperating with this pawl to form an escapement is an armature lever b¹³ of the magnet M¹⁰, this lever having a chisel edge to enter the teeth and a bar b¹⁵ to withdraw the pawl as the edge 75 enters by forcing up the tail b¹⁴ of the dog.

Opposite the ratchet the dog has a toe b¹⁷, with which coöperates a hook on the end of a spring b¹⁸ carried on the end of the armature lever of the release magnet M⁵. When 80 this armature is attracted, the pawl b¹⁶ being up, the spring reaches up, the hook takes hold of the toe and pulls down the dog, permitting the spring b¹⁰ to return the spindle b and all of its wipers to zero position.

In order to step the wheel b⁴ around, the armature lever b¹⁰ of the magnet M⁷ carries a pawl b⁷ pivoted at b⁸ on said lever and having an angle-stop b⁹ which comes against 90 a fixed stop b⁹⁰ on the bridge e², when the magnet is deenergized as shown in Fig. 1. A spring b¹⁰⁰ secured at one end to a projection on the armature b¹⁰ and at the other end to some stationary part, normally tends 95 to hold the armature b¹⁰ in retracted position as shown in Fig. 1. As the magnet M⁷ is energized its vertical lever b⁷⁰ is thrown to the left against the tension of the spring b¹⁰⁰, and a projection on the lower part 100 thereof comes against the spring b¹⁸ to remove it from the toe b¹⁷ and thus permits the retaining pawl b¹⁶ to rise into engagement with the teeth b⁶. The tension of the spring b⁸⁰ tends to keep the angle stop against the 105 fixed stop b⁹⁰ so that as the armature lever b⁷⁰ moves, its movement will cause the pawl b⁷ to swing about its pivotal point b⁸ until the pawl engages with the teeth b⁶ and advances the wheel b⁴ a space of one notch. 110 Each tooth on this wheel b⁴ will move the contact arms around over five contacts M⁶ at a jump, equal to the distance of one broad contact 48, while each tooth b⁶ moves the contact arms over one contact singly. As 115 the pawl b⁷ pushes the wheel b⁵ around, the toe b⁵¹ on the upper end of the armature lever comes over in the path of and serves as a stop for the teeth on the second wheel b⁵⁰ furnishing a positive stop for each step 120 in the rotation.

The operation of the switch is then that the action of the magnet M⁷ will advance the wipers, depending upon the number of impulses through said magnet, the pawl b¹⁶ holding the movable element in its advanced position. The action of the magnet M¹⁰ permits the movable element b⁴ to move backwardly step by step over the individual contacts M⁶ through the medium of its op- 130

erating spring b^o , the number of steps backwardly depending upon the number of impulses through said magnet M^{10} . The action of the release magnet restores all the parts 5 to their normal position by pulling down the pawl m^{10} in the manner described, and permitting the movable element b^4 to move back by the action of its spring b^o until the stop b^{40} thereon comes against the legs of 10 the bridge as shown in Figs. 1 and 3.

Having thus described my invention, I claim:

1. In an automatic telephone exchange switch, contacts arranged in groups, each 15 group constituting trunk terminals, a switch contact, and means to bring said switch contact into active relation with the last contact of a definite group of said contacts, and means to cause said switch contact to step 20 backwardly until it becomes operatively associated with one or another of said contacts in said group.
2. In an automatic switch, for telephone exchanges, a series of contacts in circular relation, a concentrically mounted arm sweeping over said contacts, and means to cause 25 said arm to make long steps in one direction and relatively shorter steps or movements in the opposite direction.
3. In an automatic switch for telephone exchanges, a spindle, two wheels on said spindle, and two pawls coöperating with 30 said wheels, one to set the wheels forward by long steps, and the other to move the wheels 35 rearwardly by short steps.
4. A switch for automatic telephone exchanges comprising a base having a stationary portion and a relatively movable part thereon, a bank of circularly-arranged terminal contacts mounted on the stationary part, and a concentrically mounted element 40 on the movable part of the base and co-operating with the contacts, means for operating said element in long steps and separate means for operating said elements in 45 relatively shorter steps, electromagnetic devices for controlling the respective stepping means, said stepping means being supported on the movable part of said base.
5. In a switching mechanism, a plurality of terminal contacts arranged in an arc shaped row and an underlying base or support provided with parallel ways, a base plate detachably connected to the support 55 and fitted in said ways, a revoluble element journaled on the plate to coöperate with said contacts and mechanism for operating said element comprising two sets of stepping devices, one for long and one for short steps 60 which mechanism is also carried on the movable plate.
6. In a progressively movable switch for automatic telephone systems, the combination with a row of terminal contacts and a

movable contact element coöperating therewith, a movable part having ratchet teeth arranged in two series in opposite directions, a vibrating arm having an engaging portion to contact with one set of teeth and a pivoted pawl to engage the other series of 70 teeth, and means for vibrating said arm as and for the purpose specified.

7. In a progressively movable switch for automatic telephone systems, the combination with a row of terminal contacts and a movable contact element coöperating therewith, ratchet wheels having relatively short and long teeth, a series of auxiliary ratchet teeth arranged in opposite directions from the teeth in the wheel, and a vibrating 80 part having a pawl for turning said ratchet wheel and an engaging part for engaging the auxiliary teeth to prevent overthrow, as and for the purpose specified.

8. In a progressively movable switch for automatic telephone systems, the combination with a row of terminal contacts and a movable contact element coöperating therewith, ratchet wheels with relatively long and short teeth and pawls for engaging the 90 same, of a series of auxiliary teeth or stops and an engaging part operating with a pawl and adapted to engage said stops and limit the throw of said pawl when the switch is being moved in long steps. 95

9. In a progressively movable switch for automatic telephone systems, the combination with a row of terminal contacts and a movable contact element coöperating therewith, a movable element, and a ratchet wheel 100 moving with said element, a spring for moving said element to its normal position, a holding pawl operating against the tension of said spring, and an escapement pawl adapted to operate in connection with said holding pawl to permit the wheel to turn backwardly step-by-step by the coöperation of said escapement and holding pawls, as set forth. 105

10. In an automatic switch for telephone exchanges, groups of terminals arranged in a row, a contact arm therefor, and means to cause said arm to move over said terminal groups to the end of the desired group, and then to step backwardly to select a contact in 110 said group. 115

11. In an automatic switch for telephone exchanges, sets of trunk terminals arranged in groups, a contact arm therefor, and electromagnetic means to cause said arm to move over said groups to the last set of terminals therein, and then to move backwardly to select a contact set in said group. 120

12. In an automatic switch for telephone exchanges, the combination with a selector apparatus having a movable contact member and groups of contact terminals arranged in a row with which said member coöperates, 125

means for moving said contact member past said contact terminals to select a group thereof, and means for controlling the return of said member to effect the selection of a contact terminal in the selected group.

13. In an automatic switch for telephone exchange systems, the combination with a selector switch comprising a spring-retracted movable brush and a row of line terminals arranged in groups, electromagnetic means for moving said contact member past said terminals to select a group thereof, and an escapement mechanism including a magnet to release said brush step by step to effect the

selection of a contact terminal in the selected group.

14. In an automatic switch for telephone exchanges, a bank of contacts, a contact arm therefor, and means to cause said arm to make long steps in one direction and relatively shorter steps in another direction.

In testimony whereof, I have hereunto set my hand this 25th day of January 1910.

CHARLES L. GOODRUM.
